Patented Dec. 25, 1917,

Inventor:

Frank Apted
By Erie Maudelke
Attorney.

UNITED STATES PATENT OFFICE.

FRANK APTE, OF GEELONG, VICTORIA, AUSTRALIA.

HAND APPLIANCE FOR DETACHING MUD OR OTHER ADHESIONS FROM FOOTWEAR OR LIKE ARTICLES.

1,251,321.

Specification of Letters Patent. Patented Dec. 25, 1917.

Application filed July 9, 1917. Serial No. 179,601.

To all whom it may concern:

Be it known that I, FRANK APTE, a subject of the King of Great Britain and Ireland, and a resident of the city of Geelong, 5 in the parish of Corio, county of Grant, State of Victoria, Commonwealth of Australia, and whose post-office address is 42 Villamanta street, in the said city of Geelong, have invented a new and useful Improved Hand Appliance for Detaching Mud or other Adhesions from Footwear or Like 10 Articles, of which the following is a specification.

This invention relates to the removal of 15 mud or other objectionable material from boots, shoes and like articles and has for its object to provide a cheap, simple and effective device by which the mud or dirt may be expeditiously removed without damage 20 to the footwear or like article.

The invention has been designed to remove such adhesions in an effective and speedy manner without injury to the footwear or like article. Previously a knife has 25 generally been employed for scraping soiled footwear. In such cases the blade is liable to injure the leather or cut the stitches, particularly if the point is inserted to remove foreign material from between the sole and 30 the upper.

The object of this invention is to provide a comparatively light strong durable and 35 convenient scraper to remove dirt, clay or other tenacious material from footwear or the like without soiling or injuring the hands of the operator. By the invention adhesions may be removed from boots, shoes or like articles in a convenient and expeditious manner without the possibility of 40 injury to the leather or the stitches. The scraper is capable of removing adhesions from heels of any size or shape, the hollow around the back of the heel can be cleansed and from the waist and sole of a boot or 45 shoe by slightly altering the angle at which the scraper is applied, or using either of the two devices furnished.

In addition to its usefulness as a scraper to the soldier, the sportsman or other user 50 of footwear, it may be employed for the purpose of lifting a lid or cover from tins or like containers, such as those in which dressings for footwear are usually put up.

Referring to the drawings which form a part of this specification:—

Figure 1 represents a portion of a blank which is so cut along the dotted line as to form two scrapers.

Fig. 2 represents a scraper made from the blank.

Fig. 3 represents a section through A—A, Fig. 2, showing a single beveled scraping edge.

Fig. 4 is a plan of Fig. 2, but showing a modified handle. A portion is broken away 65 for convenience of illustration.

Fig. 5 shows a portion of a blank which is so cut along the dotted lines as to form two modified scrapers.

Fig. 6 shows a modified scraper formed 70 from one of the blanks shown in Fig. 5.

The invention may in whole or part be fabricated from off cuts or other scraps or pieces of material and is so designed that it may be readily hung upon a nail or other 75 support.

The invention may be cut from a blank as seen in Fig. 1 in such a manner that one or more strips of metal are produced as indicated by the dotted line. Each of these has 80 a body or handle portion 3, a rounded point 5 and a broad scraping edge 6. Through each strip two or more rivet holes 7 may be formed.

The material leading to the rounded point 85 5 is preceded by a curved tapered portion 8. This is also twisted, the upper edge being back set and the lower edge 9 is set forwardly. The lower or scraping edge 9 may be of the bevel section shown at 10 in Fig. 3. 90

The material leading to the broad scraping edge 6 is bowed as at 11 also seen in Figs. 2 and 4. This broad scraping edge is also beveled as at 20 in Fig. 3. The scraping edges 6 and 9 are of such a character 95 that they do not abrade or scratch or otherwise injure the article to be scraped.

The strip when bent into shape as illustrated in Fig. 2 is provided with indent portions 12 and meeting portions 13 which are 100 united by passing a rivet 19 or the like through the holes 7.

The body or handle portions 3 serve to form a handle as shown in Fig. 2 by which the scraper may be suspended on a nail or 105 the like; or the members of the body por-

tion 3 may be partially closed together, except at the portion 3^A, such portion 3^A being looped to form an eye by which the scraper may be suspended from a nail or the like.

- 5 In the latter embodiment suitable sectioned handles 15 are used. These may be of wood or other suitable material or materials. They are preferably secured to the body portion by rivets 16.
- 10 If desired the broad scraping edge 6 may be dispensed with and the blank cut as shown in Fig. 5. The rounded end 6 or 17 may be bent back to form a scraping roll 18 as shown in Fig. 6, the tapered portion 8 being curved and twisted as before mentioned.

With the invention the removal of mud or dirt from positions around the upper and between the upper and the sole of foot-
20 wear is readily effected by the scraping edge 9 and the rounded point 5 which will readily enter and remove dirt from crevices and seams. The broad scraping edge may be used after the manner of a hoe and is par-

ticularly adapted for removing obstinate 25 mud or adhesions from the back or front of the heel and underneath the instep and sole.

Having now described my invention, what I claim as new and desire to secure by Letters Patent is:

1. A hand-operated scraping implement, consisting of a single strip of metal bent transversely upon itself to form a body portion and a pair of closely-associated scraping arms, one of which terminates in a 35 curved and twisted portion tapering to a rounded point.

2. A hand-operated scraping implement, consisting of a single strip of metal bent transversely upon itself to form a body 40 portion and a pair of closely-associated scraping arms, one of which terminates in a curved and twisted portion, the other arm having an outwardly-curved terminal portion.

In testimony whereof I affix my signature.

FRANK APTED.
